of Ohio

Application September 19, 1946, Serial No. 133,432

Term of patent 14 years

(Cl. D48—23)

To all whom it may concern:

Be it known that we, Clyde Shuler and Harold L. van Doren, citizens of the United States, and residents of Media and Ardmore, counties of Delaware and Montgomery, respectively, and State of Pennsylvania, have invented a new, original, and ornamental Design for Luminous Trough for Lighting Fixture, of which the following is a specification, reference being had to the accompanying drawing, forming a part thereof.

In said annexed drawing:

Figure 1 is a perspective view showing the luminous trough for lighting fixture our new design, the characteristic features of our design residing in the portions shown in full lines;

Figure 2 is a side elevation of the luminous trough illustrated in Figure 1;

Figure 3 is a bottom plan view of the trough illustrated in Figure 2;

Figure 4 is an end elevation of the trough illustrated in Figure 2; and

Figure 5 is an enlarged cross sectional view taken on line 5—5 of Figure 3 showing the surface configuration and general contour of the translucent panels of the trough.

We claim:

The ornamental design for a luminous trough for lighting fixture, as shown and described.

CLYDE SHULER.
HAROLD L. VAN DOREN.
